UNITED STATES PATENT OFFICE.

EBENEZER HILL, OF SOUTH NORWALK, CONNECTICUT.

REFRIGERATING APPARATUS AND METHOD OF USING THE SAME.

SPECIFICATION forming part of Letters Patent No. 244,601, dated July 19, 1881.

Application filed May 21, 1881. (No model.)

To all whom it may concern:

Be it known that I, EBENEZER HILL, of South Norwalk, in the county of Fairfield and State of Connecticut, have invented new and 5 useful Improvements in Refrigerating Apparatus and Method of Using the Same, of which the following is a specification.

This invention pertains to certain improvements in machinery for refrigerating purposes 10 and method of using the same, in which cold air or other equivalent gas is alternately compressed, cooled, and expanded to produce the cold required. One plan now in use is to supplement the power of the expanding-engines 15 by attaching a prime motor directly to them, and therefore a power-engine is required for every air engine or pump and expanding-engine. Another plan is to compress the air all 20 that is possible by the power of the expanding-engine, and to pass this same air through a compressor driven by some other motor which will add the required extra power. This last plan is used in two ways: first, the prime 25 motor compresses the air taken from the compressors which are driven by the expanding-engines, and thus completes the compression, or the prime motor takes air from the atmosphere and delivers it partially compressed to the other compressors, which then complete 30 the compression.

My method differs from these various plans or methods in providing a prime-motor engine for driving an air-compressing engine to supply compressed air entirely independent of 35 the expanding-engines, but which, when the air is compressed, may be discharged directly into the pipes which supply the expanding-engines, and therefore whatever the speed of this prime motor may be it will determine the 40 speed of the expanding engine or engines, as the case may be. Furthermore, by such an arrangement a prime motor and a compressing-engine of sufficient capacity to supply a large number of expanding-engines may be 45 centrally located, as in the vicinity of a market, and thus furnish compressed air to numbers of small expanding-engines located in refrigerating rooms or boxes, and thus a large district may be supplied with cold air from a 50 central point or station, and with only one machine to be cared for by a skillful engineer.

In the drawings, Figure 1, Sheet 1, repre-

sents a plan of my system of refrigerating apparatus with only one chill-room. Fig. 2, Sheet 2, represents a chill-room and expanding-engine with a peculiar arrangement of the pipes for circulating the air. 55

The same letters refer to corresponding parts shown on both sheets.

A is the chill-room or apartment to be cooled, 60 and should, of course, be air-tight and with non-conducting walls.

B is the air-expanding engine, in which the air, after compression, is reduced to a very low 65 temperature by work done in driving an air-compressing engine, as at C, which in this case is directly connected by the piston-rod, as at D. The expanding-engine is shown at Fig. 1 as located directly in the chill-room, but it may be in another compartment, as represented in Fig. 2, Sheet 2, and which will be 70 explained hereinafter.

The prime-motor engine is shown at E, and its compressor at F, and they may be located at a great distance from a chill-room and take 75 the air to be compressed from any source, or the compressor may be supplied from the warmer air drawn from the chill-room. The compressed air from F is conducted to the cooling-chamber at G, which is supplied with 80 tubes like a surface-condenser, as at G', and through which water circulates to cool the air. It then passes to a second chamber, H, filled 85 with tubes, as shown at H', where it is further cooled from the partially-warmed air drawn from the chill-room through a suction-pipe at K, and which supplies the suction side through pipe L of the compressor at C, which is driven by the expanding-engine in the chill-room, and the air so cooled and under pressure passes to 90 the expanding-engine at B, where it drives the compressor C, and thus becomes exceedingly cold, when it escapes into the chill-room, and after cooling the articles in said room, or thereby having its temperature increased, is again 95 drawn off by the compressor C; or it may be drawn to the compressor at F, or only a part to F and a part to C, as desired.

At 1 and 2 are shown traps for removing 100 any water that may be deposited by the compressed air after passing through the coolers.

Instead of the expanding-engine being located in the chill-room, as shown at B, Fig. 1, it may be placed in a separate compartment,

as at M, Fig. 2, Sheet 2, where a compound engine is represented with cylinders N and O and an interheater between them at P. This apartment M has a pipe, R, leading from the 5 warmest part of the chill-room, so that the warmest air in the room may be drawn directly off or out of it; and for the better accomplishment of such an object the said suction-pipe R may be made of canvas, to be 10 flexible and easily moved about, and may have a funnel-shaped mouth, as at S, to be placed directly over an article, as a cask of beer, &c., when first introduced into the chill-room, so that the heat from said cask will be 15 drawn at once from it before it can escape into other portions of the room. Said suction-pipe may be suspended, as shown, in any portion of the room by cords or loops, as at T, and to 20 keep it in tubular form it may have the ordinary form of spiral supports, as at W, or be held distended by hoops. The exhaust of 25 these engines is thrown into the chill-room through a blast-nozzle, as at X, which is surrounded by a hood or funnel, Y, of the proper shape to give a strong blast or circulation of 30 air in the chill-room. The object of this arrangement of the apparatus is to draw out the warmest air of the chill-room, and by bringing 35 it in close contact with the expanding-engines and their interheater to extract all possible heat from it and use it for doing work in driving the compressors. This apartment M may be of any required size, and, in fact, may be so small as to include merely the jackets of 40 the engines and the interheater, or "cooler," if the term be preferred.

Markets, or large blocks of buildings, stone houses, &c., could thus be easily cooled from a central engine for initial compression, and 45 then have small expanding and compressing engines in the apartments or connected with them.

The same governing agent for the large engine will also act as the governing agent for 45 all the lesser ones.

It is evident that various modifications of the apparatus may be made without departing

from the nature of my invention, as already suggested.

I therefore claim—

50

1. In a system of dynamic refrigeration, an independent air-compressing engine to act as a prime motor of the system by compressing a body of air separate and in addition to the air compressed by the other compressors of the 55 system, as hereinbefore set forth.

2. In a system of dynamic refrigeration, a central and independent air-compressor with suitable connections to one or more expanding-engines connected with a chill room or rooms 60 in such a manner that the air may be used over and over as long as desired.

3. In a refrigerating apparatus, the combination of a cooling-chamber with the chill-room and a pipe leading the air from the 65 warmer parts of the room to the suction side of the air-compressor, as hereinbefore set forth.

4. The combination of the blast-nozzle with the discharge-pipe of an air-expanding engine for conducting the air into the engine-room 70 from a flexible suction-pipe in the chill-room, and producing a strong current therein, as hereinbefore set forth.

5. The combination of the cooling-chambers, one for cold water and the other for cold air 75 from the chill-room, with an air-compressor, as and for the purposes set forth.

6. In a system of dynamic refrigeration, the method of supplying air under pressure as a prime motor to cooling and expanding and 80 compressing apparatus connected with a chill-room, and returning the same air to supplementary or initial compressors, whereby the maximum variations of mechanical force applied to the air may be utilized, as hereinbefore set forth.

In witness whereof I have hereunto subscribed my name and affixed my seal in the presence of two subscribing witnesses.
